UNITED STATES PATENT OFFICE.

MEYER BERMAN, OF NEW YORK, N. Y.

SHOE LACE.

Application filed November 2, 1923. Serial No. 672,430.

To all whom it may concern:

Be it known that I, MEYER BERMAN, a citizen of the United States, and a resident of the city of New York, borough of Manhattan, in the county and State of New York, have invented a new and Improved Shoe Lace, of which the following is a full, clear, and exact description.

This invention relates to improvements in shoe fasteners, and has particular reference to an improved shoe lace.

An object of the invention is to provide a shoe lace which, after being applied to a shoe and tied, will permit of the shoe being removed from a foot without untying the lace.

Another object is to provide a shoe lace of simple and inexpensive construction wherein a resilient body is provided with non-resilient ends, which may be readily tied and which after being tied will securely remain in fastened position.

The above and other objects will appear more clearly from the following detail description, when taken in connection with the accompanying drawing, which illustrates a preferred embodiment of the inventive idea.

In the drawing—

Figure 1 is a perspective view of a shoe showing the improved lace applied thereto;

Figure 2 is a plan view of the lace; and

Figure 3 is a fragmentary plan view, partly broken away to show the manner of attaching an end portion of the lace to the main section thereof.

Although the lace is shown as applied to a high shoe, it will be understood, of course, that the same may be used in connection with low shoes with equal facility. The lace may be used in connection with a shoe 4 having the usual rows of eyelets 5 therein for receiving the lace. The main section 6 of the lace is made of any suitable flexible and resilient material, preferably of tubular for-

mation in cross section and of any desired 45 length depending upon the nature of the shoe. The length of the main section is such that when the shoe is completely laced the ends of said main section will terminate at points contiguous to the top eyelets of the 50 shoe, thus imparting a maximum flexibility when the shoe is laced. Each end of the main section 6 is designed to receive an end portion 7 which may be secured to the main section by stitches 8 or any other suitable 55 fastening means. The end portions 7 of the lace are provided with the usual tips 9 and made of any suitable flexible material which is not elastic. The end portions 7 are of such length that when the lace is applied to 60 the shoe said end portions may be tied into a knot and bow, as shown in Figure 1.

After the lace is properly applied to the shoe and tied, the fact that the main section of the lace is resilient will permit of considerable relative movement between the sections of the upper portion of the shoe adjacent their meeting edges which are secured together by the lace. This stretching of the main section of the lace, due to its resiliency, 70 will permit of the foot being withdrawn from the shoe and again inserted into the same without untying the lace. Making the ends of the lace of non-resilient material rather than of the same material as the body 75 makes the ends easier to tie, as they will not then stretch, and also better maintains the ends in fastened condition.

What is claimed is:

A shoe lace comprising an intermediate 80 elastic portion and non-elastic extremities, the length of the intermediate elastic portion being sufficient to coact only with the lace engaging elements of the shoe, and the non-elastic ends extending beyond the lace 85 engaging elements to afford a non-elastic tying portion.

MEYER BERMAN.
